CARBURETOR FOR INTERNAL COMBUSTION ENGINES

Filed Nov. 10, 1928

Inventor:

FRANK LIoud.

by his Attorney: P. Haddam.

UNITED STATES PATENT OFFICE

FRANK LIQUID, OF ST. ETIENNE, FRANCE

CARBURETOR FOR INTERNAL-COMBUSTION ENGINES

Application filed November 10, 1928, Serial No. 318,387, and in France November 24, 1927.

The present invention relates to a carburetor for internal combustion engines having two float chambers or constant level tanks each feeding a liquid one for feeding a light 5 fuel, and the other feeding heavy fuel, the feed to the engine being as known effected so that at starting the mixture consists only of the light fuel and air whereas during normal running the two liquids are simultaneously supplied but in variable proportion according to the speed of the engine.

The invention consists in the construction and arrangement of the parts as will be hereinafter described and claimed.

15 The annexed drawings illustrate examples of construction of the invention.

Fig. 1 is a horizontal section on line 1—1 of Fig. 2, the jet holders being removed;

20 Fig. 2 is a vertical section on line 2—2 of Fig. 1 passing through the two main jets and through the atomizer;

25 Fig. 3 is a section of the construction of the nozzle for the heavy fuel when it is situated above the level of the liquid and in which it is provided with a calibrated air-orifice;

Two constant level tanks 1 and 2 contain the light and heavy fuel respectively, which fuels are respectively fed to the main jet by ducts 3 and 4 and calibrated submerged jets 30 5 and 6, carried by jet-holders 7 and 8 arranged in wells or chambers 9 and 10 formed in the carburetor body. The main jet comprises a central air inlet tube 11 having its inlet above the constant level $x-y$ of the liquids, and forming, with a member 12, an annular passage 13 for the light fuel which flows from the well 9 through a channel 35 into the chamber 14 with which the passage 13 communicates. This tube 11 is in communication with the aforesaid passage 13 below the level $x-y$ by means of calibrated orifices 19. A second member 15 in the form of a cap and having its top edge bevelled, forms with the aforesaid member 12, a second 40 annular passage 16 for the heavy fuel which flows from the well 10 through a channel 36 into the chamber 17 with which the passage 16 communicates.

45 The passages 13 and 16 both open into the main inlet channel 18 of the carburetor, but

at different heights the mouth of the passage 13 being at a slightly higher level than the mouth of passage 16 so as to avoid mingling the two liquids in case of an accidental flooding of the tank 2 for the heavy fuel.

55 On the other hand, the conical upper edge of the member 15 so directs the jet of atomized fuel that the mixture is as completely effected as if both the members 12 and 15 terminated in the same plane.

60 The central air supply through the tube 11 and above the level $x-y$ of the liquids allows the omission of a tube thus facilitating the construction; moreover capillarity leakages are prevented.

65 At stoppage of the engine a reserve of fuel is accumulated in the tube 11.

70 The jet-holder 7 of the light fuel is bored as at 20 and has at its upper end a calibrated air orifice 21. The atomization of the petrol consequently commences as soon as the communication holes 22 between the jet-holder and the well 9 are no longer submerged.

75 For a certain time therefore this jet works as a submerged jet, thus avoiding a stoppage or flat-spot in the carburation and by changing the jet-holder so as to vary the height of the holes 22 with regard to the constant level $x-y$, one can ascertain the most perfect position of these holes for any given motor.

80 The slow-running jet 30, is independent of the jet 5 and has two calibrated orifices in relation with each other: one 23 for the air, and a second 24 for the mixture.

85 Air is admitted through the calibrated orifice 23 of the screw 33 and the light fuel is fed from the tank 1 through a channel 25 (shown in dotted lines in Fig. 1) into an annular passage 34 formed in the screw 33 and passes through the radial ducts 34^a where it is met by the current of air and conveyed in the form of mixture through the calibrated orifice 24 and duct 26 to the motor.

90 The calibrated orifice 23 for the air is intended:

1. To facilitate starting;
2. To obtain complete atomization of the fuel admitted during slow-running;
3. To allow the use of larger jet having less tendency to become obstructed.

In Fig. 2 the jet 6 for the heavy fuel is submerged and under the direct influence of the suction but in the modification of construction illustrated in Fig. 3, the jet-holder 8 is hollow and has at its upper part, a calibrated orifice 28 enabling the suction to be varied on the jet 6 which, in this case, is situated above the constant level x y . This arrangement allows of increasing the diameter 10 of the calibration by reduction of the load and of the suction applied.

What I claim as my invention and desire to secure by Letters Patent of the United States is:—

15 1. A carburetor having a horizontal main inlet channel to the engine and twin float chambers respectively feeding different liquids, one a light fuel and the other a heavy fuel, to the engine in accordance with the 20 working thereof, the main jet feeding into said horizontal channel comprising a central air inlet tube having its inlet above the constant level of the liquids in said float chambers, a second tube having its outlet in said 25 horizontal channel surrounding said air inlet tube and forming therewith an annular passage for the light fuel, and a third tube having its top edge bevelled and below the outlet of said second tube and forming therewith 30 an annular passage for the heavy fuel, the central air tube being in communication with said first mentioned annular tube below the constant level of the liquids by means of calibrated orifices formed in said air inlet tube, 35 the liquids being fed to said annular passages from wells formed in the body of the carburetor through calibrated jets carried by jet-holders in said wells.

2. A carburetor as in claim 1 wherein the 40 calibrated jets are situated below the constant level of the liquids.

3. A carburetor as in claim 1 wherein the jet-holder in the light fuel well is provided at its upper end and above the constant level 45 of the liquid with a calibrated air admission orifice.

4. A carburetor as in claim 1 wherein the calibrated jet carried by the jet-holder in the well for heavy fuel is situated above the constant 50 level of the liquid, a calibrated air inlet being provided in the upper end of said jet-holder.

5. In a carburetor as in claim 1, the provision of a slow-running jet independent of 55 the main jet comprising a screw plug inserted in the body of the carburetor, said screw plug having two calibrated orifices in relation with each other, one for air and the other for 60 mixture, an annular passage for receiving fuel from a channel communicating with the light fuel tank and radial ducts conveying said fuel from said annular passage to a position between said calibrated orifices where it 65 is mixed with air from the first calibrated

orifice and conveyor through the second calibrated orifice into a duct leading to the horizontal main inlet channel.

In witness whereof I have signed this specification.

FRANK LIODU.
